UNITED STATES PATENT OFFICE.

EDWARD W. N. BOOSEY, OF DETROIT, MICHIGAN.

BACK-PRESSURE FLOOR DRAIN.

Application filed August 20, 1928. Serial No. 300,915.

This invention relates to back pressure floor drain and the object of the invention is to provide parts for a drain which may be fitted into the hub of an ordinary drain pipe 5 and will act efficiently as a drain and as a check preventing back water from backing up through the drain.

Another object of the invention is to provide a back pressure floor drain of the character described in which all of the parts are readily accessible or removable for replacement or repair.

A further object of the invention is to provide a back pressure floor drain which will 15 allow access to the interior of the drain pipe for cleanout purposes and which is equipped to allow the drain to be readily flushed with an ordinary hose when desired.

A further object of the invention is to provide a back pressure floor drain including 20 a swing check valve for preventing back water from backing up through the drain, the said swing check valve being removable in its entirety from the drain for inspection, replacement or repair without disarranging the other parts of the floor drain.

These objects and the several novel features of the invention are hereinafter more fully described and claimed, and the preferred form of construction by which these objects are attained is shown in the accompanying drawings in which—

Fig. 1 is a plan view of a back pressure floor drain embodying my invention.

Fig. 2 is an enlarged section taken on line 2—2 of Fig. 1.

Fig. 3 is a reduced section taken on line 3—3 of Fig. 2.

The construction of the device is shown 40 more particularly in Fig. 2 and comprises a drain pipe 1 having a hub 2 providing a shoulder 3. A hubbed drain pipe of this type is standard and is carried in stock by most plumbers. A substantially cup shaped member 4 is positioned on the shoulder 3 and is provided with a series of lugs 5 which are embedded in the caulking 6 between the member 4 and the hub 2 which holds the member 4 in place. At the upper edge, the member 4 is provided with a series of notches 7 and the caulking is carried up to the bottom of these notches so that any drainage passing onto the caulking will pass through the notches 7 into the interior of the member 4. A 55 perforated drain plate 8 is positioned on the upper edge of the member 4 and extends

flush with the upper edge of the hub 2, and the hub may be embedded in a concrete floor as shown, which extends flush with the upper edge of the hub 2. As shown in Figs. 2 and 3, the member 4 is provided with two apertures 9 and 10 in the bottom. A plug 11 is threaded into the aperture 9 and may be removed for cleaning out the drain pipe 1. This plug 11 is provided with a square boss 60 12 to which a wrench may be applied for its removal, and a machine screw 13 extends through the drain plate 8 and is threaded into the plug 11. This screw 13 secures the drain plate and member 4 together and holds the 70 drain plate in place in the hub 2.

A valve body is threaded into the threaded aperture 10 in the bottom of the member 4 and is provided with four lugs 15, as shown in Figs. 2 and 3, to which a wrench may be 75 applied to thread or unthread the valve member 4 into or out of the threaded aperture 10. This valve body is formed with a portion of smaller diameter opening therefrom from one side of the center forming a conduit 16 80 having a sloping bottom and the conduit terminates in an opening 17 extending in a vertical plane. A rib 18 is cast integrally with the valve body directly over the opening 17 and an arm 19 is pivotally mounted 85 at 20 on the rib 18. A circular valve 21 is provided, having a boss 22 which is apertured to receive the arm 19, and a set screw 23 is provided for securing the arm 19 in the boss 22. By this arrangement, the valve 21 normally seats by gravity on the end of the conduit 16 and prevents back water from passing upwardly through the said conduit, and at the same time allows drainage to flow 90 downwardly through the conduit 16 opening 95 the swing check valve and passing to the interior of the drain pipe 1. As shown in Figs. 1 and 2, the drain plate 8 is provided with an aperture 24, and a plug 25 is positioned in this aperture and is provided with drainage 100 apertures 26 in the bottom and with a rib 27 by means of which the plug 25 may be lifted out of the aperture 24. The plug 25 is provided with a flange 28 which seats on a companion face provided about the aperture 105 24 in the drain plate 8. This plug 25 may be readily removed to allow insertion of an ordinary hose for washing out the interior of the swing check valve which is positioned directly therebeneath.

The swing check valve is also so constructed that the valve 21 and arm 19 and the boss

22 and set screw 23 are within the outer diameter of flange 14, so that the valve body, including the swing check valve, may be unthreaded and withdrawn through the aperture 10 for inspection or repair without disturbing the member 4 and caulking in which the said member is set. This swing check valve may also be readily replaced, as the entire valve may be readily inserted through 10 the aperture 10 and may be secured to the member 4 by threading, as shown, or in any other suitable manner.

When it is desired to flush the entire drain, or to clean out the drain pipe 1, the screw 13 15 may be removed to allow removal of the drain plate 8, at which time, the plug 11 may be unthreaded from the member 4 to allow access to the drain pipe 1 for clean-out purposes. Due to the sloping bottom of the conduit 20 16 leading toward the swing check valve 21, it is impossible for dirt or foreign matter to accumulate within the swing check valve and thus the water flowing through the swing check valve will keep the conduit 25 clean and, at the same time, the swing check valve will automatically prevent back-water from backing up through the drain.

From the foregoing description, it becomes evident that the device is very simple and 30 efficient in operation, will not easily get out of order, may be readily cleaned out at any time, will prevent water from backing up through the drain and provides a device which accomplishes the objects described.

35 Having thus fully described my invention, its utility and mode of operation, what I claim and desire to secure by Letters Patent of the United States is—

1. A back pressure floor drain comprising 40 a drain pipe having an enlarged hub at the upper end and forming an annular shoulder, a substantially cup-shaped member seating on said shoulder within the hub and having a series of external lugs, the space between said 45 cup-shaped member and the hub being filled with caulking and embedding the lugs therein, said cup-shaped member being provided with a series of notches in the upper edge and the caulking being carried up to the bottom 50 of said notches, a pair of threaded apertures in the bottom of the cup-shaped member, a clean-out plug threaded into one of the apertures, a swing check valve threaded into the other aperture to a position flush with the 55 bottom of the cup-shaped member, the swing check valve being inseparable through the threaded aperture therefor and preventing back water from backing up through the drain, a drain plate positioned on the notched upper edge of the cup-shaped member and extending flush with the end of the hub, a screw 60 extending through the drain plate and threaded into the clean-out plug and a removable plug mounted in the drain plate directly over said swing check valve.

2. A back pressure floor drain comprising a drain pipe having an enlarged hub at the upper end forming an annular shoulder, a substantially cup-shaped member seating on said shoulder and caulked in position thereon, the upper edge of said cup-shaped member being provided with notches above the caulking, a drain plate resting on said notched edge and extending flush with the hub end of the drain pipe, said cup-shaped member being provided with a pair of apertures in the bottom open to the interior of the drain pipe, a clean-out plug secured in one of said apertures, a screw extending through the drain plate and threaded into the clean-out plug, a swing check valve body secured in the other aperture and having a conduit opening therefrom into the interior of the drain pipe, the said conduit having a sloping bottom and a swing check valve pivotally mounted on said valve body and normally closing said conduit by gravity, the swing check valve and conduit being freely movable through the opening in which said valve body is secured. 70 75 80 85 90

3. A back pressure floor drain comprising a drain pipe having an enlarged hub at the upper end forming an annular shoulder, a substantially cup-shaped member seating on said shoulder and secured in position thereon, said cup-shaped member being provided with a pair of apertures in the bottom, a clean-out plug secured in one aperture, a swing check valve including a valve body having a portion of large diameter secured in the other aperture, a conduit opening therefrom at one side of the center thereof and having a sloping bottom, a swing check valve pivotally mounted on said body and normally closing the discharge end of said conduit by gravity, the conduit and swing check valve being 100 freely movable through the aperture for the portion of the valve body of large diameter, a drain plate mounted on the upper edge of said cup-shaped member and extending flush with the upper edge of said hub and a removable plug in the drain plate directly over said swing check valve. 105 110 115

4. A back pressure floor drain comprising a hubbed drain pipe, a cup-shaped member fitting within the hubbed portion of the drain pipe and caulked in position therein, the upper edge of said cup-shaped member being provided with notches, a drain plate resting on said notched upper edge and extending flush with the hubbed end of said drain pipe, said cup-shaped member being provided with a pair of apertures in the bottom open to the interior of the drain pipe, a clean-out plug threaded into and closing one of the apertures, a swing check valve body extending through and secured in the other aperture and having a conduit opening into the interior of the drain pipe and a swing check valve normally closing said conduit by gravity. 120 125 130

5. A back pressure floor drain comprising a drain pipe having an enlarged hub at the upper end forming an annular shoulder, a substantially cup-shaped member seating on said shoulder and secured in position thereon, said cup-shaped member being provided with a pair of apertures in the bottom, a clean-out plug secured in one aperture, a swing check valve secured in the other aperture and ar-

ranged to prevent water from backing up 10 through the drain and a drain plate mounted on the upper edge of said cup-shaped member and extending flush with the end of the hub.

In testimony whereof I sign this specifica- 15 tion.

EDWARD W. N. BOOSEY.
